CLAIM

The ornamental design for a balloon bug, as shown and described.

DESCRIPTION

FIG. 1 is a top perspective view of the balloon bug showing my new design;

FIG. 2 is a bottom perspective view thereof;

FIG. 3 is a top plan view thereof;

FIG. 4 is a bottom plan view thereof;

FIG. 5 is a right side elevational view;

FIG. 6 is a left side elevational view thereof;

FIG. 7 is a front elevational view; and,

FIG. 8 is a rear elevational view thereof.

The broken lines depicting the balloon structure in the drawing have been shown for the purpose of illustrating environment that forms no part of the claimed design.
